UNITED STATES PATENT OFFICE.

WILLIAM H. ISBISTER, OF PHILADELPHIA, PENNSYLVANIA, ASSIGNOR -TO
A. J. HOLMAN & CO., OF SAME PLACE.

DESIGN FOR A MOUNTING FOR BOOK OR ALBUM COVERS.

SPECIFICATION forming part of Design No. 31,849, dated November 21, 1899.

Application filed August 2, 1899. Serial No. 725,930. Term of patent 7 years.

To all whom it may concern:

Be it known that I, WILLIAM H. ISBISTER, a citizen of the United States, residing in the city of Philadelphia, State of Pennsylvania, 5 have invented and produced a certain new and original Design for a Mounting for Book or Album Covers, of which the following is a full, clear, and exact description, reference being had to the accompanying drawings, forming 10 a part of this specification.

My invention relates to a mounting for book and album covers; and it consists in the novel form and configuration thereof, substantially as shown in the accompanying drawings.

15 Figure 1 is an elevation of the ornamental mounting, showing the form and configuration thereof. Fig. 2 is a section on the line 1 2 of Fig. 1.

The design as shown in the drawings consists in an ornamental mounting the form of

which has the general shape of a five-pointed star with an open square center A. The inner edges b of the square center A are above the horizontal plane of the outer edges c of the whole ornament, said outer edges c of the 25 star-shaped sides being inclined downward, whereby the body portion of the ornamental mounting is raised above the plane of its edges in what may be called "alto-rilievo."

What I claim is—

30 The design for a mounting for book and album covers, substantially as herein shown and described.

In testimony whereof I have hereunto affixed my signature this 28th day of July, A. D. 35 1899.

WILLIAM H. ISBISTER.
